UNITED STATES PATENT OFFICE.

ADOLPH ROTHSCHILD, OF PADUCAH, KENTUCKY, ASSIGNOR OF ONE-HALF
TO JOE FRIEDMAN, F. M. FISHER, AND W. F. PAXTON, OF SAME PLACE.

AUTOMATIC DUMPING-CAR.

SPECIFICATION forming part of Letters Patent No. 560,369, dated May 19, 1896.

Application filed November 5, 1895. Serial No. 568,018. (No model.)

To all whom it may concern:

Be it known that I, ADOLPH ROTHSCHILD, a citizen of the United States, residing at Paducah, in the county of McCracken and State of Kentucky, have invented a new and useful Automatic Dumping-Car, of which the following is a specification.

The invention relates to improvements in dumping-cars.

10 The object of the present invention is to improve the construction of dumping-cars, especially those designed for carrying coal and other heavy material, and to provide a simple and inexpensive one which will enable its 15 entire contents to be quickly dumped without necessitating shoveling at its ends.

The invention consists of the construction and novel combination and arrangement of parts hereinafter fully described, illustrated 20 in the accompanying drawings, and pointed out in the claims hereto appended.

In the drawings, Figure 1 is a perspective view of a dumping-car constructed in accordance with this invention, one of the folding 25 end skids being raised and the other being arranged against the adjacent end wall and bottom portion of the car. Fig. 2 is a longitudinal sectional view of the same. Fig. 3 is a transverse sectional view. Fig. 4 is a detail 30 sectional view illustrating the manner of mounting the rack-bars and pinions. Fig. 5 is a detail view of one of the curved shields. Fig. 6 is a detail view of the operating-lever.

Like numerals of reference designate 35 corresponding parts in all the figures of the drawings.

1 designates a dumping-car having its side and end walls arranged vertically and provided at the center of its bottom with a 40 pending hopper 2. The hopper is provided at its bottom with hinged gates or doors 3, which are connected at their free edges by chains 4 with a transverse windlass-shaft 5. The windlass-shaft 5 is provided with a crank-handle, which may be removable or be formed 45 integral therewith, and the shaft is held against retrograde rotation by a pawl and ratchet 6. When it is adapted to dump the car, the pawl is thrown out of engagement 50 with the ratchet and the weight of the mate-

rial in the hopper will open the gates or doors 3.

In order to empty the material from the entire car without shoveling and without decreasing the capacity of the car by providing 55 permanent inclined end walls forming a continuation of those of the hopper, folding skids 7 are arranged in the car at each end thereof. Each folding skid consists of upper and lower sections 8 and 9, connected at their adjacent 60 edges by a pintle-rod 10, and constructed of any suitable material, the eyes for the pintle-rod 10 being preferably formed integral with metal strips or bars 11 and 12, arranged at intervals on the upper and lower sections. 65 The upper edge of the upper section is hinged to the top of the car at the adjacent end thereof by an upper transverse pintle-rod 13, and the lower edge 14 of the lower section is beveled and is adapted to slide freely on the 70 bottom of the car when the sections of the skid are raised to an inclined position in alignment with each other to form a continuation of the adjacent inclined wall of the hopper. When the skid is arranged in its folded 75 position, the sections fit squarely against the bottom and end wall of the car and do not decrease the capacity thereof and are not subjected to any strain when not in use. The skid-sections may be constructed either of 80 wood or metal, and when of the former the edge 14 of the lower section is protected by a suitable metal strip, as illustrated in the accompanying drawings.

The skid-sections are raised from their 85 folded position at right angles to each other to an inclined position to shoot the material into the hopper by curved rack-bars 15 and short windlass-shafts 16, carrying pinions 17, which mesh with the curved rack-bars. The 90 curved rack-bars are arranged at the inner faces of the sides of the car and are provided at their lower ends with eyes 18, which receive the ends of the pintle-rod 10. The short windlass-shafts are located at each side 95 of the car and pass through the sides, the pinions being arranged on the inner ends of the shafts within suitable keepers 19 and the outer ends of the shafts being adapted to receive an operating-lever 20 and carrying 100

ratchet-wheels 21, which are engaged by pawls 22, pivotally mounted on the car.

The teeth of the rack-bars are arranged at the upper edges thereof, and the lower edges 5 of the rack-bars are supported within the keepers 19 by antifriction-rollers 23. The keepers 19 are disposed substantially horizontal on the inner faces of the sides of the car, and the outer ends of the short windlass- 10 shafts are supported by suitable brackets 24. The operating-lever 20 is provided at one end with an eye to receive the short windlass-shaft, and it is secured thereon by a pin 25, and adjacent to the eye the operating-lever 15 is provided with a pivoted dog 26, adapted to engage the teeth of the ratchet-wheel 21 to rotate the windlass-shaft 16, whereby the rack-bars are moved upward.

In order to prevent the teeth of the rack-bars from becoming filled with coal-dust or other accumulation, the sides of the car have 20 secured to them curved shields 27, substantially triangular in cross-section and presenting inclined faces adapted to shed the coal 25 and dust. The upper section 8 of each folding skid is provided at its end adjacent to the pintle 10 with recesses 28, which receive the curved shields 27, and which causes the skids to clear the same.

30 It will be seen that the dumping-car is exceedingly simple and inexpensive in construction, that it is capable of rapidly discharging its entire contents without necessitating shoveling, and that its capacity is not decreased, 35 as it has vertical end walls and horizontal bottom portions. It will also be apparent that the car is not weakened by its dumping attachment, and that the folding skids may be readily applied to cars of the ordinary construction without necessitating any alteration 40 thereof.

Changes in the form, proportion, and minor details of construction may be resorted to without departing from the principle or sacrificing any advantages of the invention.

45 What I claim is—

1. The combination with a car, of a folding skid composed of two sections hinged together

and similarly connected to the top of the car and adapted to fit against the end and bottom thereof when not in use, curved rack-bars connected with the skid and located at the sides of the car on the inner faces thereof, gearing arranged to mesh with the rack-bars to raise and lower the same, and shields 55 mounted on the car and arranged to exclude dust from the teeth of the rack-bars, substantially as described.

2. The combination with a car, of a folding skid composed of two sections hinged together 60 and similarly connected to the top of the car and adapted to fit against the end wall and bottom when not in use, curved rack-bars connected with the sections and arranged on the inner faces of the sides of the car, curved 65 shields mounted on the car and located above the rack-bars and having inclined faces adapted to shed the material to prevent the teeth of the rack-bar from becoming clogged, pinions meshing with the rack-bars, and wind- 70 lass-shafts connected with the pinions and adapted to raise the rack-bars, substantially as described.

3. The combination with a car, of a folding skid composed of two sections hinged together 75 and similarly connected to the top of the car and adapted to fit against the end and bottom thereof when not in use, curved rack-bars connected with the folding skid at the point of hinging, extending upward from the 80 skid and located on the inner faces of the sides of the car, pinions meshing with the rack-bars and mounted on the inner faces of the sides of the car, windlass-shafts connected with the pinions and extending through the 85 sides of the car, and pawl-and-ratchet devices mounted on the outer faces of the sides and connected with the windlass-shafts, substantially as described.

In testimony that I claim the foregoing as 90 my own I have hereto affixed my signature in the presence of two witnesses.

ADOLPHI ROTHSCHILD.
